UNITED STATES PATENT OFFICE.

OLIVER U. PERRIN, OF STONE BLUFFS, INDIANA.

MOWER.

SPECIFICATION forming part of Letters Patent No. 439,253, dated October 28, 1890.

Application filed January 6, 1890. Serial No. 336,101. (No model.)

To all whom it may concern:

Be it known that I, OLIVER U. PERRIN, a citizen of the United States, residing at Stone Bluffs, in the county of Fountain and State 5 of Indiana, have invented an Improved Mechanism for Operating Mowing-Machines, of which the following is a specification.

My invention relates particularly to an improvement in reciprocating mowers, and has 10 for its object to produce a machine of the character described, in which the operating mechanism is very simple, durable, and efficient.

With these objects in view my invention 15 consists in the peculiar construction of various parts and their novel combination, as will be more fully explained hereinafter.

In the drawings forming a part of this 20 specification, Figure 1 is a perspective view 20 of my improved machine. Fig. 2 is a top plan view. Fig. 3 is a detail view of the wheel and ratchet. Fig. 4 is a detail view of the shoe-coupling, hand and thumb levers, pawl, ratchet, &c.

25 In the embodiment of my invention I use a main frame A, essentially rectangular in shape, said frame being of wood or metal, and connected with the opposite sides of said frame are the journal-boxes A', through 30 which passes the axle A², upon the ends of which are mounted the drive-wheels A³. The axle-spindles are provided with the ratchet-wheels a, and the hub of each of the wheels is formed with a recess adapted to receive 35 said ratchet-wheel and also a spring-actuated pawl pivoted to said hub and adapted to engage the ratchet. By this construction the axle will be rotated when the machine is moving forward, but will not move when the 40 machine is backed.

A wheel B is rigidly secured to the axle-shaft within the main frame, one face of said wheel being serrated radially, as shown at b, and upon the axle adjacent to the serrated 45 side of the wheel is arranged a rigid collar B', in which the axle turns, and in which is pivoted the vibrating lever C, the axle passing through said lever or not, as desired. The wheel B has an uneven number of serrations, 50 and the face of the lever C that rests against said wheel is formed to correspond with said

serrations. The lever has no vertical movement, and is vibrated horizontally by the serrated wheel B, with which it is in engagement.

D indicates the tongue or draft-pole, and, if desired, the singletree may be attached, as shown.

The under side of the frame is provided with two pairs of parallel lugs E, between 6c which are pivoted the inner ends of the coupling-yoke E', said yoke members uniting and supporting the shaft F, which is provided with the ratchet-faced enlargement f near its outer end, the purpose of which will appear 65 further on.

A shoe-coupling G is journaled upon the outer end of the shaft F, said coupling having a lever G' rigidly connected therewith at its top and extending inwardly toward the driver, 70 said lever having a thumb-lever g, which operates a spring-actuated pawl g', which is pivoted to the shoe-coupling and adapted to engage the ratchet-faced enlargement f and hold the coupling at any desired angle. H 75 indicates the shoe, and H' the finger or guide bar, and H² is the reciprocating cutter-bar. H³ indicates a link-connection between the draft-pole and shoe. The outer end of the vibrating lever is formed with a ball, which fits into a socket in the end of the pitman-rod I, and is held in said socket by means of the socket-cap i. The outer end of the pitman is also provided with a ball, which fits in a socket-cap i², secured to the cutter-bar. 80 A lever K is pivoted to the upper side of the frame near the driver's seat, said lever having a link-arm k connected therewith, which in turn is connected with a chain or rope k', attached to the coupling-yoke, and by elevating or depressing the lever the coupling, cutter, &c., are raised or lowered. The chain passes over a pulley or sheave k², mounted on the side of the frame. By means of the hand 85 and thumb levers the cutter-bar can be arranged at any suitable angle.

S indicates the driver's seat.

The operation and advantages of my improved device are obvious to every one skilled in the art to which it pertains.

100 What I claim as new, and desire to secure by Letters Patent, is—

In a mowing-machine, the combination, with the main frame having the tubular axle-bearings projecting laterally from both sides of the frame, of the axle passing through said 5 bearings, the rigid collar mounted loosely upon the axle between the tubular bearings, a ratchet-faced wheel secured upon the axle within the frame, and adapted to turn with

the said axle, and a vibrating lever pivoted in the rigid collar and adapted to engage the ratchet-faced wheel, substantially as shown and described.

OLIVER U. PERRIN.
